CONE-MAKING MACHINE.

Application filed May 23, 1921. Serial No. 471,963.

The principal objects of this invention are to increase the capacity of production of ice cream cones and to reduce the cost and to devise a machine which may be operated 5 continuously and will be easily manipulated.

The principal feature of the invention consists in the novel construction and arrangement of parts whereby a plurality of 10 moulds are operated to successively pass a charging member and in the interval the cones are moulded, baked and discharged progressively.

In the drawings, Figure 1 is a diagrammatic plan view of our improved apparatus, showing two units of a circular multiple unit arrangement.

Figure 1^A is an elevational view of the cam tracks for operating the mould sections.

Figure 2 is an enlarged part vertical sectional view through one of the units taken at the charging point.

Figure 2^A is a sectional view of one of the cores.

Figure 3 is an enlarged plan view of one of the moulds.

Figure 4 is an enlarged sectional view of one of the moulds.

The present invention is modelled on a 30 particular scheme of operation that will render continuous production very simple by arranging a plurality of moulds to operate on a circular table or trackway and to continuously rotate.

In the form of the invention herein shown, a pair of concentric circular foundation blocks 1 and 2 are provided with a plurality of surface rollers 3 upon which are rotatably mounted the circular plates 4 and 5. At in-

40 tervals around the circular plates are arranged the supporting brackets 6 and 7 which project over the space between the circular blocks and on the inner portions of these brackets are carried the paired parallel 45 rods 8. Upon the rods 8 are mounted the mould blocks 9 which are divided longitudinally and are formed with the mould pockets 10 which are the shape of the cone. Each 50 of the blocks 9 is provided on its outer face with pairs of brackets 11 carrying rollers which engage the face grooves 12 of the cams 13 arranged upon the transverse shafts 14 supported in suitable bearings arranged

upon the plates 4 and 5.

55 These shafts are operated in unison to turn

in opposite directions by means of the intermeshing spur gears 15 arranged upon the outer ends thereof and upon the rotation of these shafts the cams 13 move the mould sections apart or move them together. 60

One of the gears 15 is provided with a pin 16 and a cam track 17 is arranged adjacent to the outer block 2 to engage this pin and rotate the gears a half turn thus turning the shafts 14 and through the cams 13 and brackets 11 moving the mould sections apart, said sections sliding freely on the parallel rods 8. A second cam track 17' is arranged to engage the pin 16 and turn the gears a half turn back thus closing the 70 moulds together.

The mould sections 9 are each formed hollow and open at the underside and supported beneath said moulds are gas burners 18 which throw their flame up into the hollow 75 mould blocks and around the exterior of the cone moulds thus heating the moulds to bake the cones.

At a point in the circumference of the machine adjacent to the second cam track 17' there is arranged a device for charging the moulds. This consists of a receptacle 19 supported upon a rigid support and from this receptacle extends a tube 20. This tube is formed with a double chamber and in the lower chamber is arranged a rotatable dispensing member 21 which is formed with pockets 22, which upon the rotation of the said dispensing member carry a definite quantity of the batter from which the cones 90 are made and drop it into the moulds as they pass therebeneath.

The inner rotatable plate 4 supports a plurality of standards 23, each having a horizontally extending arm 24 in which are 95 slidably mounted the rods 25. At the lower end of these rods is supported a cross bar 26 on which are mounted the cone-shaped cores which are adapted to extend into the moulds to form the batter placed therein the 100 desired thickness.

The mould blocks 9 are formed with raised flanges 28 along their outer longitudinal edges to prevent the overflow of batter from the moulds and the cores 27 are provided 105 with rings 29 at the base which are adapted to cut off any overflowing batter and also to form a bead at the edge.

The cores are hollow and are heated by a gas burner 30 extending transversely over 110

the top thereof. The upper and lower gas burners are fed by flexible tubes 31 and 32 connected with a ring 33 which is supplied by a pipe 34 which is carried on a swivel bearing in the centre of the machine and swings around with the device as it rotates, feeding gas to the ring 33.

The core bars 26 are operated by means of cam trackways 35 and 36 suitably supported by standards 37 and 38. These trackways engage rollers 39 arranged upon the upper end of the rods 25. The trackways are so shaped as to move the cores downwardly and upwardly at the proper periods.

The feeding of the batter is effected through the rotation of the dispensing member 21. This is accomplished by means of a pinion 40 on the outer end which engages 20 a gear face 42 supported on the rotatable plate 5 which thus operates the gear as it passes thereunder. The rings 4 and 5 are driven in any suitable manner, a motor 43 being here shown geared to a gear ring 44 secured to the outer plate 5.

In the operation of this device, the receptacle 19 is filled with batter. The motor 43 is started and the structure supported on the rollers 3 is revolved. The mould blocks 30 9 are closed together by the cams 17' prior to the movement of the mould beneath the dispensing tube 20 and as the moulds pass beneath the dispensing tube the member 21 is turned so as to drop a measured quantity 35 of batter directly into the mould pockets. When each mould moves past the dispensing member, the cores 27 are caused to move downwardly by the slope of the cam tracks 35 and 36 and the batter is spread 40 out over the entire surface of the mould.

It will be noted that there is a slight period between the depositing of the batter in the moulds and the lowering of the cores thereinto. This allows any steam formed 45 through the first contact of the batter with the hot mould to escape. Any excess batter flowing out of the top of the mould will be cut to a uniform shape by the ring flanges 28 and it is prevented from overflowing the side of the mould blocks by the flanges 28.

The rotation of the structure carries the moulds around the circle, each one being charged as described as it passes under the dispensing device and as the moulds ap-

proach the dispensing device the baking of the cones is completed and the mould sections are operated by means of the shafts 14 and cams 13 to separate. The separating action of the moulds occurs prior to the lifting of the cores so that both mould sections pull away from the baked cones and they drop through on to a suitable table. The cores are then lifted up by means of the cam tracks so as to pass over the dispensing member.

It will be seen that a machine constructed as described may be operated continuously and its output will be continuous. The device being of circular form is compact and 70 will be very easily handled.

What we claim as our invention is:—

1. A cone making machine, comprising, a pair of concentric circular members rotatably mounted in a horizontal plane, brackets 75 mounted on the circular members supporting paired parallel rods, mould blocks arranged in pairs slidably mounted on said rods, rotatable cam members arranged parallel with an outside of each of said mould blocks, means operatively connecting said rotatable cam members to operate in unison in opposite directions to operate to close said blocks and to move said blocks apart, means arranged in the path of movement of the rotatable members adapted to operate said cam means at predetermined intervals, cores for said moulds, vertical guides for 80 said cores, means for raising the cores at predetermined intervals, means for feeding batter to the moulds while the cores are raised, and means for heating said pairs of moulds individually and continuously.

2. A cone making machine, comprising, a circular rotatable member, a plurality of slideways arranged around said circular member, a plurality of moulds each formed of a pair of separable blocks arranged on said slide-ways, rotatable cam wheels operatively connected with each of said blocks, intermeshing spur gears connected with each pair of cams, stationary cam tracks adapted to engage and rotate said gears to effect the separation of each pair of mould blocks at a predetermined point in the rotation of the circular member to discharge the finished cones and to close and lock the moulds, and means for charging the moulds.
